COMBINATION ARTICLE CARRYING AND SUPPORTING DEVICE

William H. Wheeler, New York, and Ann L. Jacobsen,
Poughquag, N. Y.

Application December 17, 1952, Serial No. 22,750

Term of patent 14 years

(Cl. D58—26)

Fig. 1 is a side elevation view of a combination article carrying and supporting device, showing our new design;

Fig. 2 is an end elevational view thereof;

Fig. 3 is a top plan view of the article supporting portion thereof, shown in flattened position;

Fig. 4 is a side elevational view of the article carrying portion thereof, shown in article carrying position; and

Fig. 5 is an enlarged sectional view of an individual slat of the article carrying portion thereof as taken on the line of a tie member passing through a slat.

The characteristic feature of our combination article carrying and supporting device is the uniform close spacing of a group of slats centrally of the sling portion thereof and the progressive increase in the spacing between slats in the end portions of said sling as they are more remote from said central group.

We claim:

The ornamental design for a combination article carrying and supporting device, as shown and described.
